US0D1060371S

(12) **United States Design Patent** (10) **Patent No.:** **US D1,060,371 S**
(45) **Date of Patent:** **** Feb. 4, 2025**

(54) **MONITOR STAND**

(71) Applicant: **KUNSHAN HONGJIE ELECTRONICS CO., LTD.**, Suzhou (CN)

(72) Inventor: **Xiaojie Chang**, Jiangsu (CN)

(**) Term: **15 Years**

(21) Appl. No.: **35/520,972**

(22) Filed: **Apr. 8, 2024**

(80) **Hague Agreement Data**

Int. Filing Date: **Apr. 8, 2024**

Int. Reg. No.: **DM/237091**

Int. Reg. Date: **Apr. 8, 2024**

Int. Reg. Pub. Date: **May 24, 2024**

(30) **Foreign Application Priority Data**

Nov. 7, 2023 (CN) 202330725396.6

(51) **LOC (15) Cl.** **14-02**

(52) **U.S. Cl.**

USPC **D14/452**
